UNITED STATES PATENT OFFICE.

LEVI F. KNODERER, OF COLUMBUS, OHIO.

STAND-BOILER.

SPECIFICATION forming part of Letters Patent No. 768,859, dated August 30, 1904.

Application filed March 3, 1904. Serial No. 196,834. (No model.)

To all whom it may concern:

Be it known that I, LEVI F. KNODERER, a citizen of the United States, residing at Columbus, in the county of Franklin and State of Ohio, have invented a certain new and useful Improvement in Stand-Boilers, of which the following is a specification.

My invention relates to an improvement in stand-boilers.

10 The object of the invention is to provide an efficient and simple heating means in combination with a casing entirely surrounding the boiler whereby the products of combustion are caused to circulate around the latter, 15 thus being thoroughly exhausted of their heating properties before escaping.

Another feature resides in the burner, which is so formed as to be readily assembled and placed in position beneath the boiler. A 20 further novel point lies in an integral ring plate, which will be hereinafter referred to.

Finally, the object of the invention is to provide a device of the character described that will be strong, durable, efficient and one that 25 will be comparatively simple and inexpensive to construct and also one in which the parts will not be liable to get out of working order.

With the above and other objects in view the invention consists of the novel details of 30 construction and operation, a preferable embodiment of which is described in the specification, and illustrated in the accompanying drawings, wherein—

Figure 1 is a vertical sectional view. Fig. 35 2 is a top plan view of the ring. Fig. 3 is a detail partial sectional view of the burner.

Similar numerals refer to similar parts throughout the several views.

In the drawings the numeral 1 designates 40 the boiler, which is of the ordinary construction and is provided with the usual inlet-pipe 2 and outlet-pipe 3 and the clean-out pipe 4, having the cock 5. The boiler 1 is inclosed by a cylindrical casing 6, formed with an out- 45 let 7 near its upper end, which is suitably connected with a proper flue. The casing 6 is larger in diameter than the boiler, thus forming a chamber around which the products of combustion circulate. The lower end of

the casing rests on a ring plate 8 and is held 50 in place by the guard-flange 9. Upwardly-extending lugs 10 from the plate 8 are formed with seats 11, in which sets the lower peripheral end of the boiler. I preferably employ three of the lugs, as shown in Fig. 2, although 55 I may use more. The ring plate 8 is supported by an ordinary stand 12, provided with the usual curved arms 13, which are held in fixed relation to the plate 8 by the downwardly-projecting annular flange 14. It is 60 evident that the flange allows a ready assembling of the plate and the stand, whereby the same are fixedly secured together in a simple and efficient manner. It is to be observed that the guard-flanges 9, lugs 10, annular 65 flange 14, and lip 18 are formed integral with the ring plate 8, thus providing a plate which may be cast, thereby greatly simplifying the construction of the device.

For heating the boiler I employ a gas-burner 70 comprising a cylindrical mixing-chamber 15, having an open lower end and a flaring upper end 16, formed with a laterally-projecting annular flange 17, by which the burner is supported in an annular lip 18, formed in the 75 ring plate and having its upper surface flush with the ring plate. Gas is supplied to the chamber 15 by a pipe 19, where it is mixed with air entering through the lower end of the chamber to form a combustible product. 80 Supported centrally and flush with the upper end of the mixing-chamber is a deflector-plate 20, resting on legs 21, formed integral with the chamber, and provided with contracted ends 22, which pass through apertures in the plate 20 and which may be upset to secure the plate in place. The plate is smaller in diameter than the opening at the end 16, which, owing to its flaring walls, radiates the products which pass upward around 90 the edge of the deflector-plate 20.

The products having been ignited and passing up against the plate 20 are deflected thereby against the flaring walls of the end 16, by which they are radiated, passing around 95 the edge of the said plate. The radiating or spreading of the products causes them to circulate upward around the boiler within the

casing, thereby thoroughly heating the boiler and escaping through the outlet 7 practically spent.

It is wholly within the province of my invention to arrange within the mixing-chamber 15 a suitable gasolene-burner, as it may be desirable to use gasolene as a fuel instead of gas.

It is apparent that the device is quite simple and that a greatly-increased heating of the boiler is attained through the casing and the burner.

I do not wish to limit myself to the exact details of operation and construction herein set forth, as I may make various changes in the same without departing from the spirit of my invention.

Having now fully described my invention, what I claim as new, and desire to secure by

Letters Patent, is—

1. In a device of the type set forth, a boiler, a casing inclosing the same, a stand therefor and a burner, in combination with a ring plate having a central opening and comprising, a guard-flange engaging the casing, lugs formed with seats to receive the boiler, an annular flange engaging the stand, and a lip formed about the opening and adapted to support the burner.

2. In a device of the type set forth, a boiler, a casing having an outlet and inclosing the boiler, a ring plate having a central opening, a guard-flange engaging the casing, lugs projecting upwardly from the plate and supporting the boiler, an annular projecting flange, a stand supporting the plate and engaging said flange, a lip formed on said plate adjacent the opening, a burner having a flaring end supported upon said lip, a deflector-plate supported in the end of the burner, and means for supplying fuel to the burner.

3. In a device of the type set forth, a boiler, a casing having an outlet and surrounding the boiler, a plate having a central opening and supporting the boiler and the casing, a stand for supporting the plate, in combination with a burner comprising a cylindrical mixing-chamber having a flaring end supported by the plate within the opening thereof, a deflector-plate within the flaring end of the chamber, legs from the chamber for supporting the plate, and means for supplying fuel to the burner.

LEVI F. KNODERER.
